(57) CLAIM

The ornamental design for a aromatherapy patch, as shown and described.

DESCRIPTION

FIG. 1 is a perspective view thereof of a aromatherapy patch showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

In the drawings, the stippled areas depict a powder applied to the surface of the aromatherapy patch and forms no part of the claim.
